UNITED STATES PATENT OFFICE.

COLUMBUS A. BOWSHER, OF CHAMPAIGN, ILLINOIS.

TELLURIAN.

SPECIFICATION forming part of Letters Patent No. 548,798, dated October 29, 1895.

Application filed October 18, 1894. Serial No. 526,258. (No model.)

To all whom it may concern:

Be it known that I, COLUMBUS A. BOWSHER, of Champaign, in the county of Champaign and State of Illinois, have invented certain new and useful Improvements in Tellurians; and I do hereby declare that the following is a full, clear, and exact description thereof, reference being had to the accompanying drawings, and to the letters of reference marked thereon, which form a part of this specification.

This invention relates to improvements in that class of educational apparatus known as "tellurians," and especially designed to illustrate the yearly movement of the earth around the sun, its daily rotation upon its own axis, and the varying effects of heat and cold, daylight and darkness resulting therefrom, and producing the change of seasons and the alternations of day and night.

The object of the invention is to provide an improved construction in devices of the character referred to; and it consists in the matters hereinafter set forth, and particularly pointed out in the appended claims.

In the accompanying drawings, Figure 1 is a side elevation of a tellurian constructed in accordance with my invention. Fig. 2 is a fragmentary top plan view of the middle part of the frame and the dial. Fig. 3 is a vertical section taken on line 3 3 of Fig. 1.

In said drawings, A designates the main frame of the tellurian, and B a vertical supporting standard upon which said frame A is mounted to revolve in a horizontal plane. Preferably, and as herein shown, the framework A is composed of a longitudinal metallic beam A', made T-shaped in cross-section and provided between its ends with a bearing a for the upper end B' of the standard B. Said bearing a and the adjacent portion of the standard B are furthermore herein shown as inclosed within a sheet-metal casing A², which is secured at its upper edges to the beam A' and converges downwardly therefrom to engage the standard B at a point somewhat below the bearing a, so as to steady the framework upon the standard. For the purpose, also, of reducing the friction as far as possible, the entire weight of the tellurian is sustained by a pivot-screw a', which passes

through a rigid longitudinal bridge-bar A³ of the frame and rests with its point within a suitable depression in the top of the standard B. Said bridge-bar A³ is in this instance secured to the frame by means of screws a², which pass through the ends of the bar and enter upwardly-projecting lugs a³ of the beam A', and the pivot a' is designed to be locked in its adjusted position within said bridge-bar by means of a jam-nut a⁴. The lower end of the standard B may be of any desired shape, but is herein shown as a plain cylindric rod adapted to be inserted and clamped within a suitable base. (Not shown.)

At one end of the frame A is located a clock-work motor C, which is preferably, and in this instance, arranged beneath the general level of the top of the frame A and is provided with a fan-governor C', of a usual type, by which its movement is rendered substantially uniform. A vertical driving-shaft C² projects downwardly from the motor and is provided at its lower end with a sprocket-pinion C³, which is connected by a sprocket-chain C⁴ with a fixed sprocket-gear B² on the standard B. With this construction it is obvious that as the motor-shaft C² revolves the entire framework A will be caused to rotate upon the standard B through the reaction of the sprocket-wheel C³ and chain C⁴ upon the stationary gear B², and the direction of such rotation is arranged to be opposite to the direction of rotation of the hands of the watch. The sprocket-wheels C³ and B² are furthermore in this instance shown as provided with projecting lower flanges c and b, which serve to support the sprocket-chain C⁴ and obviate any tendency of the latter to sag away from the gears and rid the sprockets of the same.

At the other end of the frame A from that at which the motor C is located a globe or sphere D is revolvably mounted upon the upper end e of a rotary spindle E, the lower end e' of which is journaled in a vertical bearing A⁴ on the frame A. Between its ends the spindle E is oppositely bent in two directions, so that its upper end e is inclined at an angle of twenty-three and one-half degrees to the vertical, while at the same time the center of the globe D stands directly above the bearing A⁴. In other words, the shape of the

spindle E is such that the axes of its two end portions $e e'$ intersect each other at the center of the globe D. The sprocket-gear E' is rigidly secured to the lower portion e' of the spindle just above the upper surface of the frame A, and a similar gear B³ of equal size is rigidly mounted in the same plane therewith upon the upper end B' of the standard B, between the bridge-bar A³ and the top of the beam A, said bridge-bar being long enough to permit the insertion of the gear between the lugs a³ of the beam. A sprocket-chain E² connects the gears B³ and E' and causes the latter to rotate relatively to the frame A as the latter is revolved upon the standard B.

The globe D is mounted to revolve freely upon the upper end of the spindle E, but is rigidly attached to a toothed gear D', which is sleeved upon said spindle so as to rotate independently thereof. Said gear D' intermeshes with a surrounding circular rack F, preferably made somewhat conical in shape, so that its tooth f will stand parallel to the axis of the gear D' at the moment of their engagement therewith. The rack F is arranged concentric with the bearing A⁴ of the spindle E, and is herein shown as supported by columns F', secured to a base-plate F², which rests upon the beam A'. With this construction it is obvious that the relative rotation of the gear E' and spindle E with relation to the frame A as the latter revolves on its standard will cause the gear D' to travel around the interior of the rack F and produce a rotation of the said gear and of the globe D to which it is attached in exact imitation of the rotation of the earth upon its axis. It will also be obvious, however, that owing to the equal diameters of the gears E' and B³ the apparent rotation of the gear E' will exist solely with relation to the frame A, and that said gear E' will actually remain stationary, so far as rotation upon its axis is concerned. Consequently the axis of rotation of the globe D will always point in the same direction in the same manner as the axis of the earth constantly points toward the north star.

The bearing A⁴ for the lower end of the spindle E is herein shown as including a suitable bearing-aperture a⁵ in the beam A', through which the end e' of the spindle is passed, and a pivot-screw a⁶, carried by a suitable yoke a⁷, upon the point of which the lower end of the spindle rests. By screwing said pivot-screw a greater or less distance into the yoke the vertical adjustment of the globe D may be varied as desired, and the screw may be thereafter secured against displacement by means of a jam-nut a⁸. This form of bearing is obviously not only adjustable but reduces the friction to a minimum.

The sprocket-chain E² is prevented from sagging unduly by lower flanges e² and b' of the sprocket-wheels E' and B³, respectively, as in the case of the sprocket-wheels C³ and

B². The sprocket-wheel B³ is furthermore herein shown as provided with an upper flange B⁴, which is graduated to form a dial marked to indicate the four seasons of the year—spring, summer, autumn, and winter—and, also, preferably divided to indicate the three months constituting each season. A pointer A⁵, supported at the center of the cross-bar A³, is also provided to co-operate in the indications of such dial.

At the opposite end of the frame A from the globe D or at that end adjacent to the motor C is provided a standard G, which may support any suitable device or framework representing the sun or the rays thereof; and that half of the globe D remote from the standard G is herein shown as covered by a hemispherical hood H indicating the unilluminated surface of the globe. A skeleton cage H' of hemispherical form is also herein shown as covering the other half of the globe D for the purpose of indicating the several zones in which the heating effects of the sun are felt to various degrees. All these latter features, however, have been already set forth in my previous patent, No. 457,487, dated August 11, 1891, and in themselves form no part of my present invention.

I claim as my invention—

1. A tellurian, comprising a supporting standard, a rotary frame pivotally mounted upon the upper end of the standard, a motor on said frame provided with a sprocket gear, a stationary sprocket on the standard, and a sprocket chain connecting the two gears, whereby the rotation of the motor and sprocket will cause the frame to revolve upon the standard, substantially as described.

2. A tellurian, comprising a supporting standard, a rotary framework pivotally mounted on said standard, a motor on said framework provided with a sprocket gear, a fixed sprocket gear on the standard, a sprocket chain connecting the two gears, a rotary globe carrying shaft on the frame provided with a sprocket gear, a second stationary sprocket gear on the standard, and a sprocket chain connecting the last two sprocket gears, substantially as described.

3. A tellurian comprising a supporting standard, a rotary frame pivotally mounted on said standard, a spindle mounted at one end of the frame, a globe mounted on the spindle, a motor mounted on the opposite end of the frame and forming a counter-balance for said globe, gearing connecting the motor and standard by which the frame is turned on the standard and gearing connecting the standard with the said spindle for turning the globe relatively to the frame, substantially as described.

4. A tellurian, comprising a supporting standard, a frame pivotally mounted on the upper end of said standard, a globe mounted on one end of the frame, a motor at the other end of the frame forming a counterbalance

for said globe, and a pivot screw seated in a fixed part of the frame and bearing at its point upon the upper end of the standard so as to support the weight of the frame, substantially as described.

5. A tellurian, comprising a supporting standard, a frame pivotally mounted upon said standard, the upper end of the standard projecting through the frame, a motor at one end of the frame provided with a sprocket gear, a stationary sprocket gear on the standard, a sprocket chain connecting said gears, a globe carrying spindle at the other end of the frame, a sprocket gear on said spindle, a stationary sprocket gear secured upon the upper end of the standard above the frame, a sprocket chain connecting the last two sprocket gears, a bridge bar rigidly secured to the frame spanning the gear on the upper end of the standard, and a pivot pin having a screw threaded engagement with said bridge bar and bearing at its point upon the upper end of the standard, substantially as described.

25. 6. A tellurian, comprising a supporting standard, a frame pivotally mounted on said standard, the upper end of the standard projecting through said frame, a motor on one end of the frame provided with a sprocket gear, a stationary sprocket gear on the standard, a sprocket chain connecting the two gears, a globe carrying spindle at the opposite end of the frame from the motor, a sprocket gear rigidly secured on said spindle, a stationary sprocket gear on the upper end of the standard, a dial for indicating the seasons of the year on the upper end of the standard, and a pointer on the frame adjacent to the dial, substantially as described.

40. 7. A tellurian, comprising a supporting standard, a frame pivotally mounted on said standard, a reversely bent spindle journaled

at its lower end in a vertical bearing in the frame, a globe revolvably mounted upon the upper end of the spindle, a toothed gear secured to the globe concentric with the upper end of the spindle, a circular rack or gear intermeshing with said globe gear arranged concentric with the journal of the spindle, a sprocket gear on the lower end of the spindle, 45 a stationary sprocket on the standard, a sprocket chain connecting the two sprocket wheels, a motor on the frame provided with a sprocket gear, a second stationary sprocket gear on the standard, and a sprocket chain 50 connecting the last two sprocket gears, substantially as described.

8. A tellurian, comprising a supporting standard, a frame pivotally mounted on said standard, an upwardly projecting spindle 60 journaled in a vertical bearing at one end of the frame, said bearing comprising a cylinder opening for the spindle, and a pivot screw extending through a fixed part of the frame and engaging a central recess in the end of 65 the spindle, thereby adjustably supporting the same, a globe revolvably mounted on the upper end of the spindle, said spindle being reversely bent between its ends so that the axes of said ends intersect each other at the center 70 of the globe, a gear wheel secured to the globe concentric with the adjacent end of the spindle, a circular rack or gear concentric with the lower end of the spindle and intermeshing with the globe, a motor on the frame, and 75 gearing connecting the motor with the spindle and standard, substantially as described.

In testimony that I claim the foregoing as my invention I affix my signature in presence of two witnesses.
